UNITED STATES PATENT OFFICE.

JOHN RAPIEFF, OF NEW YORK, N. Y.

AUXILIARY VALVE FOR PNEUMATIC GUNS.

SPECIFICATION forming part of Letters Patent No. 502,016, dated July 25, 1893.

Application filed September 9, 1889. Renewed November 15, 1892. Serial No. 452,049. (Model.)

To all whom it may concern:

Be it known that I, JOHN RAPIEFF, a subject of the Czar of Russia, residing in the city, county, and State of New York, have invented 5 certain new and useful Improvements in Auxiliary Valves for Pneumatic Guns, of which the following is a specification.

My invention relates to pneumatic delivery valves actuated by pressure of the compressed 10 fluid which they control, and in which the valve is maintained on its seat by the pressure applied to a predominating area on the back of the valve as opposed to the same pressure applied to a less area at the opposite 15 site or opening end of the valve; and my invention is especially applicable to such valves as used in pneumatic ordnance to perform the act of firing.

My invention consists of an improved pressure actuated auxiliary valve for exhausting and restoring the retaining pressure at the back of the delivery or "firing" valve; and the object of my improvement is to insure the 20 accuracy of the opening, dwelling, and closing periods of the firing valve and the corresponding accuracy of the range of the projectile which is dependent upon the volume of compressed air or gas delivered.

In order to enable others skilled in the art 25 to which my invention appertains to understand and use the same, I will proceed to describe its construction in detail, explain its operation, and point out in the appended claims its novel characteristics; reference being had to the accompanying drawings, in 30 which—

Figure 1, is a sectional elevation of a firing valve of the annular type, and its casing, showing the auxiliary valve with its accessories and its casing partly in section on the line $x-x$, Fig. 2. Fig. 2, is an inverted plan view of Fig. 1, showing the hand operated starting mechanism for the auxiliary valve partly in section. Fig. 3, is a sectional detail view of a pneumatic starting mechanism for the auxiliary valve. Fig. 4, is a detail view pertaining to Fig. 2. Fig. 5, is an enlarged sectional detail view of the auxiliary valve and its casing taken on the line $y-y$, Fig. 1; 40 Figs. 6, 7, and 8, similar sectional views of the auxiliary valve showing different positions thereof; and Fig. 9, a sectional view showing

a hand operated valve connective with the pneumatic starting device illustrated in Fig. 3.

The annular firing valve 1, seats at 25, and 55 retracts into the chamber 4, at the back of it, within which the valve retaining pressure is charged or exhausted.

5, is the chamber to which opening pressure is applied constantly to the opposite less 60 area of the valve 1.

2, is the annular port surrounding the valve 1, connecting with the storage reservoir.

3, is the port connecting to the gun barrel.

6, is the charging and exhausting port of 65 the chamber 4, and which the auxiliary valve 7, in casing 8, controls.

9, is the supply port connected with a pressure source, such as the storage reservoir.

10, is a throttle and stop valve controlling 70 the air supply, and governing its rate of flow into the chamber 4, returning the firing valve to its seat, being thereby capable of employment as a timing element to the firing valve.

The throttle 10, consists of a plug, the same 75 prevented from turning in its seat by a suitable feather, and adjustable upon a screw 11, having a hand-wheel 12, rotating in a permanent position.

13, is a scale indicator consisting of a sliding bar that is moved by engagement of teeth thereon with a screw thread on the periphery of the hand-wheel. There is also a graduated scale on the rim of the wheel, as indicated in Fig. 4, extending entirely about its 85 circumference and which is read from the index 14.

The valve 7, is composed of connected pistons of differential diameters, the piston 15 predominating in area over that of the piston 16. 90

18, is the exhaust passage which is opened or closed to the port 6, of the firing valve retaining pressure chamber by the movement of the piston 16. 95

The exhaust passage 18 (Fig. 1,) is regulated in capacity by an adjustable valve 19, controlling the outlet openings 20. The cap 21, which bears a scale, as in Fig. 3, is rotative upon a fixed screw 22, which gives it a gradual longitudinal motion covering or uncovering the openings 20, more or less. 23, is a jam nut for binding the cap when adjusted. 100

The space between the differential pistons

15, and 16, has constant connection with the pressure supply port 9, in all positions of the valve.

The spaces 17, 25, the passages 26, and a receiving chamber 27, are normally charged with pressure by the release of which the differential pistons are moved by the constant pressure in the interspace thereof to open the exhaust piston 16.

10 The exhaust piston 16, seats upon packings at 28, and at the advanced stroke of the valve, the larger piston 15 seats upon packings at 29.

31, is a plunger extension of the piston valve 15, the portion 30, of which fits the cylindric chamber 17, its function being to start the valve on its return stroke when pressure is applied in the chamber 17.

32, is a throttling valve for throttling or cramping the port 33, through which pressure is admitted at a given rate of flow from the receiving chamber 27, to the valve returning chamber 17.

The throttling valve 32, closes the port 33, more or less according to the advancement of its inclined surface therein, and it is rotative upon a screw thread 34, by the rotation of a cap 35, bearing an indicating scale upon its exterior as in Fig. 1.

The stem 36 engages with the slotted shank 30 of the cramping valve 32, and rotates in a fixed position, its shoulder 37, affording a packing surface.

The stem 36 is grooved to engage with a spline 38 in the cap 35, and rotates with it. 35 The cap 35, is screw threaded to the casing so that in rotation, it also moves lengthwise and may be thereby employed to indicate upon a unit scale 40 (Fig. 1), while the fractional scale 41, graduates the adjustments.

40 The valve 7, is wholly pressure operated, and there is a second valve interior to it, the initial movement of which is imparted at will, the remainder of its movements being automatic.

45 46, is the operating stem to the inner valve, and the same is provided with a stop 47, that engages with an abutment 48, composing a bearing of the stem. The abutment 48, arrests the advance stroke of the interior valve 45, before the exterior valve 7, has completed its stroke. The seating end 50, of the valve 45, controls the exhaust of the receiving chamber 27, and chamber 17, by which event the exterior valve becomes active. The interior valve 45, is of differential diameter, the end 51, predominating, whereby an opening pressure surface is obtained at 52. The passages 53, in the exterior valve connect constantly with pressure. The passages 54, connect with 50 the receiving chamber 27, as also the passages 56, when the exterior valve is normal.

When the interior valve is normal, a passage 57 therein, connects passages 53, 54; therefore admitting pressure to chambers 27, 17, 60 retaining the valve 7, on its seat 28.

When the interior valve is advanced to a certain extent passages 59, 60, 61, therein con-

nect passages 56, with the space 62, and thence about and beneath the opening end 50, of the inner valve.

63, is a passage whereby pressure from port 9, through 53, is admitted to chamber 65, to retain the inner valve on its seat when in its normal position. The passage 63, connects with chamber 65, through passages 61, 60 and 64.

The successive events of operation of the valves 7, and 45, will be hereinafter explained.

Referring now to the hand operated starting mechanism for giving initial opening to the valve 45; that shown in Figs. 1, and 2, 80 corresponds substantially to that described and claimed by me in a separate patent application, filed simultaneously herewith; and that shown by Figs. 3, and 9, and claimed herein is equally applicable to the herein described auxiliary valve, and to the one described in the said separate application or to other forms of auxiliary valves similarly operated.

In Fig. 2, 70, is the gunner's hand lever; 71, the continuation of the valve stem 46; 72 the valve stem notch; 73, the lever actuated spring pawl engaging therewith; 74, the second spring pawl moving with the first pawl engaging with a notch or spur 75, thereon, 95 when the first pawl is thrown out of the valve stem notch by the continued movement of the valve 45, beyond that imparted by hand. 76, is the tripper for disengaging the second pawl from the first pawl during the 100 retracting stroke of the lever. The lever 70, is fulcrumed at 77. The pawl 73, is fulcrumed at 78, to the lever 70, and the pawl 74, fulcrumed to the lever at 79. The advanced position of such parts is indicated by dotted 105 lines. The spring 80, is in the present instance used to counteract the pressure in the space 65, upon the inner valve 45, during the first movement of opening.

In Fig. 3, the stem 71, bears a piston 81, fitting a bushing having exhaust ports 82, which connect with the atmosphere. The piston 81, covers the exhaust ports when the valve 45 is normal, but opens them immediately after the said valve 45, has been advanced to the position of Fig. 6, and becomes self-acting. The air pipe 83, connects the pressure side of the piston 81, with the passage 84, shown in Fig. 9. The device in Fig. 9, is located at any convenient distance from the firing valve according as circumstances may require.

85, is a chamber of a limited volume, and is normally connected with a compressed air supply pipe 86, through passages 87, 88 in a puppet valve 89. The puppet valve seats 125 toward the outlet connecting to the passage 84 and pipe 83, and fits in the form of a plunger in cylindric margins of its seat. The passages 88, in the smaller plunger part of the valve are cut off when the valve is lifted from 130 its seat.

90, is the hand lever, used in lieu of the lever 70, and its heel 91, engages with the valve stem 92, to perform the act of firing.

In operation, in Figs. 3, and 9, the movement of the lever 90, first cuts off the supply pipe 86, confining a measured volume of compressed air in the chamber 85. Such movement next opens the seating aperture of the valve 89, admitting the limited volume of air to the piston 81, starting the inner auxiliary valve 45. As soon as the movement has become sufficient to exhaust the chamber 65, and the auxiliary valve is rendered automatic, the exhaust passages 82, are opened delivering the measured fluid permitting the return of the piston 81, as the auxiliary valve retracts.

Referring now to the operation illustrated by Figs. 5 to 8 inclusive, and commencing with Fig. 5, the valves are in a normal or inactive position. As the valve stem 46, advances, the events occur and result in the following order: First, the space 57, is cut off from the passages 53; severing the air supply to chambers 17, and 27. Second, the space or passage 62, is cut off from the passages 53, severing the air supply to chamber 65, this being the position in Fig. 6. Third, the exhaust end 50 of the interior valve opens, terminating the period of the gunner's control; the pressure through passages 53, becoming active on the differential area of the inner valve at 52, as the pressure in chamber 65 is exhausted moving the inner valve to the position of Fig. 7. Fourth, the passages 59, coincide with the passages 56, exhausting the chambers 27, and 17, through the core of the valve 45, and space 62, and seat. Fifth, the pressure in the interspace from 9, upon the differential pistons of the valve 7, moves the same, unseating the exhaust piston 16, disconnecting ports 6, and 9, and connecting ports 6, and 18. Both valves move together from the position assumed in Fig. 7, until the inner valve 45, is arrested by its stop 47, closing the passages 56, restoring pressure to space 65, and reseating it; while the outer valve 7, completes its advancing stroke. Sixth, the passages 26 are connected by the interspace of the valve 7, instantaneously charging the receiving chamber 27, with pressure as the valve completes its advancing stroke to the position of Fig. 8; the pressure flowing at a measured rate into the chamber 17, determining the duration of dwell of the valve 7, and the corresponding dwell of the firing valve. Seventh, the return stroke of both valves 7, and 45, together to their normal positions, by pressure upon the plunger 31, in chamber 17. As soon as the fitted part 30, of the plunger 31, leaves the chamber 17, the pressure exerts itself on the full area of piston 15, and imparts a quick stroke; the pressure being maintained as before in 17 and 27, after the valves have closed. The projection 100, acts to close the passage 64, when the interior valve is at the advancing extremity of its stroke, to prevent premature access of returning pressure to chamber 65.

The movements of the firing valve consist of an instantaneous opening movement, a va-

riable open dwell, and an instantaneous closing movement, the volume of compressed fluid delivered depending on the duration of such open dwell, and the range of the projectile being governed accordingly for a given angle of elevation of the gun.

The exhaust of the port 6, into outlet 18, by the quick stroke of the valve 7, effects the instantaneous opening movement of the firing valve. The dwell thereof is determined by the rate of flow permitted by the valve 32, by the adjustment of the indexed cap 35; and the restoration of pressure to the port 6, by the quick return stroke of the valve 7, effects the instantaneous closing movement of the firing valve to its seat.

The confined space 5, in which an opening pressure is constantly applied to the firing valve is a feature claimed by me in a separate patent application filed simultaneously herewith.

Having thus fully described my invention, what I claim, and desire to secure by Letters Patent, is—

1. The combination with a pressure actuated fluid delivery valve, of an auxiliary differential piston valve having the space between its pistons permanently connected with the pressure source, a port of the delivery valve retaining pressure chamber connected with said space between the differential pistons when the auxiliary valve is normal, an exhaust outlet exterior to the less piston and to which the delivery valve port is connected when the pistons are advanced, a receiving chamber normally charged with pressure connected by a port to the space exterior to the greater piston when the valve is normal, but connected by such port to the interspace of the differential pistons when the same are advanced, a port of regulated capacity connecting from the receiving chamber to the piston cylinder at a portion thereof beyond the range of advance stroke of the pistons, and an internal hand operated exhaust valve controlling exhaust ports, in the differential valve, whereby the said receiving chamber is exhausted for the purposes specified.

2. The combination in an auxiliary valve adapted for the purposes described, of differential connected pistons, a supply port permanently connected to the interspace of the pistons, a delivery valve retaining pressure port connected with the said interspace when the pistons are in a normal position, exhaust openings exterior to the less piston with which the said delivery valve port is connected when the pistons are advanced, a plunger exterior to the greater piston, a chamber thereof normally connected with pressure, and means, within the differential pistons for exhausting the said chamber.

3. The combination, in an auxiliary valve adapted for the purposes described, of a cylinder having differential diameters, the less end whereof is open to exhaust, the greater end being closed to exhaust and normally

- charged with pressure, differential connected cylinder pistons, the interspace whereof is permanently connected with a supply port, means, independently operative on ports 5 through the piston adjacent the closed end of the cylinder, whereby such closed end is exhausted, a receiving chamber normally charged with pressure being connected to the said closed end of the cylinder, a port of the 10 receiving chamber located in the cylinder to connect with the interspace of the pistons at or near the termination of their opening stroke and a port of regulated capacity permanently connecting the receiving chamber 15 with the closed end of the cylinder.
4. The combination with a differential connected auxiliary piston valve, adapted to control the firing valve supply and exhaust ports as specified, of a closed chamber or chambers 20 of the cylinder opposite the greater piston, and an independent exhaust valve interior to the piston valve controlling passages therein whereby the said chamber or chambers are connected with the atmosphere.
- 25 5. The combination of a primary differential piston valve, adapted for the purposes specified, a normally charged chamber or chambers exterior to its greater end, an exhaust outlet exterior to its less end, a secondary differential piston (or plunger) exhaust valve interior to said primary valve, controlling ports therein, connected to the said chamber or chambers, said secondary valve seating at its lesser end toward and 30 within the exhaust end of the primary valve, means whereby the greater end of the secondary valve is normally connected with pressure, a supplemental space 52, of the differential areas of the secondary valve constantly 35 connected with pressure; the said ports being located relatively to each other whereby the initial movement of the secondary valve will first cut off the pressure opposite the greater end thereof, and second exhaust the 40 same through its seat, and whereby the pressure becomes active upon the said supplemental space for the purposes specified.
- 45 6. The combination with the primary differential valve, and the secondary differential valve therein operative as specified, of a valve stem to the secondary valve provided with a stop, and an abutment therefor, whereby the exhaustion of the space exterior to the greater end of the primary valve is ter-

minated before the completion of the latter's 55 stroke for the purposes specified.

7. The combination of the differential piston primary valve, a closed chamber or chambers opposite the greater piston thereof, the secondary valve reciprocative within the primary valve, the passages 53, 54, in the primary valve, and the passage 57, in the secondary valve whereby the said chamber or chambers are charged when both valves are normal.

65 8. The combination with an auxiliary valve having its initial movement imparted at will, and its remaining movements automatic, of a pneumatic valve starter, consisting of an actuating piston connected to the auxiliary 70 valve, and exhaust ports in the casing of such piston normally closed by the piston but opened thereby subsequent to the completion of said initial movement of the auxiliary valve, and means, whereby a measured quantity 75 of fluid is delivered to actuate the piston.

9. The combination of the pneumatic auxiliary valve starting piston and its exhaust passages arranged as described of the confined chamber 85, the releasing valve, the 80 firing lever for opening it, and a shank of the releasing valve fitting a supply inlet, and having passages to close the same prior to the release of pressure by the opening movement of the releasing valve.

85 10. In a pneumatic gun, an auxiliary firing valve and ports controlled thereby, in combination with a secondary valve movable with and independent of the auxiliary valve, starting mechanism connected to the secondary 90 valve, exhaust and pressure ports and passages connecting the cylinders of the two valves, said ports and passages being unaffected by the starting movement of the secondary valve, an exhaust port in the cylinder 95 of the secondary valve which exhausts both ends of said cylinder upon the starting movement of said valve, and pressure surface in said secondary valve intermediate said exhausted ends, said surface in communication 100 with the pressure reservoir whereby said secondary valve is caused to automatically complete its opening stroke, substantially as described.

JOHN RAPIEFF.
